UNITED STATES PATENT OFFICE.

WILLIAM J. OSTENDORF, OF AURORA, ILLINOIS.

MUSICAL INSTRUMENT.

Application filed November 23, 1927. Serial No. 235,254.

My invention relates, more particularly, to the cupped mouth-pieces for musical instruments generally termed "brasses" and comprising cornets, trumpets, and other instruments, the mouth-piece to which my invention relates being the part which slips into the "mouth-pipe" of the instrument.

These mouth-pieces comprise a cup portion extending from the outer end of a tubular 10 stem and a terminal rim-portion at the outer end of the cup and against which the performer presses his lips in playing the instrument equipped with the mouth-piece.

It has been found in practice that to meet 15 the varying conditions, it is necessary that cups of different forms and sizes and having throat-openings of different sizes be provided, and furthermore that different sizes of tubular stem-portions be provided when the 20 mouth-piece is to be used with different instruments, as for example, cornets and trumpets, and also that different forms of lip-engaging rims be provided to meet the different requirements of the musicians.

As mouth-pieces have heretofore been provided, it is necessary that the musicians purchase a large number of mouth-pieces having 25 cups of different forms and sizes and throat openings of different sizes and stem-portions of different lengths, in order that they may have available mouth-pieces which will more, or less, adequately meet the requirements imposed by the particular conditions under 30 which the instruments are to be played.

My primary object is to provide a construction of mouth-piece which will present the 35 capability of interchange of parts required to be provided of different forms or sizes to meet the various conditions under which various "brasses" are played, thereby rendering 40 available to the musician, and at the minimum expense, a mouth-piece for any of such "brasses" exactly suited to the particular condition presented.

Referring to the accompanying drawing:

Figure 1 is a view in side elevation of a mouth-piece constructed in accordance with my invention. Figure 2 is an enlarged longitudinal sectional view of the mouth-piece, the 50 section being taken at the line 2 on Fig. 1. Figure 3 is a perspective view of a washer shown as forming a part of the construction of the preceding figures; and Figure 4, a perspective view of a throat-forming sleeve, or bushing, also forming a part of the mouth-piece.

The particular construction shown comprises a tubular stem-portion represented at 5, one end of which is shown as of tapered form, as represented at 6, at which it is adapted to be telescoped with the "mouth-pipe" of a "brass" musical instrument, the particular form of stem-portion shown being adapted for use with a trumpet. The other end of the stem-portion 6 is externally threaded as represented at 7. The mouth-piece also comprises a cup 8 presenting a passage 9 therethrough expanded at 10, adjacent an annular shoulder 11 in the cup, to form a socket 12 the outer end portion of the wall of which is internally threaded at 13 and at which the cup screws upon the threaded portion of the stem 6.

The mouth-piece also comprises a throat-forming tube, or bushing, 14 which is removably confined in the socket 12 between the shoulder 11 and the inner end of the tube 6.

The outer end of the cup 8 is externally screw-threaded as represented at 15 to adapt it to receive a rim-portion 16 having internal 80 screw-threads 17 at which it screws upon the threaded portion 15 of the cup, the rim 16 presenting an inwardly-extending flange 18 opposing the adjacent end-face 19 of the cup and between which one, or more, washers 20 85 may be confined to vary the length of the passage provided by the mouth-piece from its inlet to its throat-portion.

It will be understood from the foregoing description that a mouth-piece constructed 90 in accordance with my invention permits of the interchange of different sizes, and forms, of elements comprising the mouth-piece, preferably as shown, to provide different forms or sizes of the parts 5, 8, 14 and 16, together 95 with a supply of washers 20, to provide a mouth-piece to meet any particular presented condition, it being understood that a plurality of the throat-forming bushings 14 presenting throat-openings of different sizes 100 would be provided and likewise cups 8 of different forms and sizes and rims 16 of different shape would be provided by reason of the removability of the throat-forming bushings 14 and interchange thereof and the provision of the cups 8 as members separate from the other parts of the mouth-piece, a large 105 number of different combinations of parts may be effected, such combination being augmented by the provision of the member 5 as a separable part permitting of interchange 110 of one member 5 for another thereof of differ-

ent form or size and further by the provision of the washer feature for increasing the effective length of passage in the cup.

While I have illustrated and described a particular construction embodying my invention I do not wish to be understood as intending to limit it thereto as the same may be variously modified and altered without departing from the spirit of my invention, and in this connection it may be stated that while I have shown a mouth-piece of such construction that the interchange feature may be availed of as to all of the parts which it is desired under different conditions be provided of different sizes or forms, the invention is not limited to such a mouth-piece, as it may be incorporated in a mouth-piece in which the adaptabilities for interchange are presented by a lesser number of the elements thereof than in the construction shown.

What I claim as new, and desire to secure by Letters Patent, is:

1. A mouth-piece for "brasses" comprising a cup, a separate stem-portion detachably connected with said cup, said cup containing a ²⁵ socket presenting a shoulder and into which said stem extends, and a removable throat-forming member located in said socket and clamped in position therein by said shoulder and said stem-portion. ³⁰

2. A mouth-piece for "brasses" comprising a cup containing a socket in one end presenting a shoulder and internally threaded, a removable throat-forming member located in said socket, and a stem-portion having a ³⁵ threaded end screwed into the threaded portion of said socket and against said throat-forming member for holding the latter against said shoulder.

WILLIAM J. OSTENDORF.
